UNITED STATES PATENT OFFICE.

ROBERT WEIR, JR., OF MCKEESPORT, PENNSYLVANIA.

RAIL-JOINT.

SPECIFICATION forming part of Letters Patent No. 711,604, dated October 21, 1902.

Application filed March 18, 1902. Serial No. 98,737. (No model.)

To all whom it may concern:

Be it known that I, ROBERT WEIR, Jr., a citizen of the United States, residing at McKeesport, in the county of Allegheny and State 5 of Pennsylvania, have invented a new and useful Improvement in Rail-Joints, of which improvement the following is a specification.

This invention relates to certain new and useful improvements in rail-joints, and relates more particularly to that class wherein the use of nuts and bolts is entirely dispensed with.

The invention has for its further object a device of this character which will be extremely simple in construction, strong, durable, comparatively inexpensive to manufacture, and highly efficient in its use.

With the above and other objects in view the invention consists in the novel combination and arrangement of parts, to be herein-after more fully described, and specifically pointed out in the claims.

In describing the invention in detail reference is had to the accompanying drawings, forming a part of this specification, and where-in like numerals of reference indicate like parts throughout the several views, in which—

Figure 1 is a side elevation of my improved device. Fig. 2 is a top plan view thereof. Fig. 3 is a vertical sectional view of the same. Fig. 4 is a top plan view of the rail-joint with the rails removed therefrom.

In the drawings the reference-numeral 1 represents the rails, said rails having their 35 meeting ends formed on an angle, as shown at 2, and the sides of the web of the rails converge toward their ends, as seen in Fig. 2 and shown by dotted lines in Fig. 3, to form a wedge. The rail-joint 3 comprises integral 40 fish-plates 4, extending upwardly at an angle under the tread of the rail, as shown at 5. The upper edge of the fish-plates 4 extend at an angle, as shown at 6, and are beveled toward the center, as shown at 7 in Fig. 4 of 45 the drawings, forming a wedge-shaped clamp at the meeting ends of the rails. The said fish-plates 4 are formed integral with the base 8, forming the chair portion, extending under the under face of the base of the rail. It will 50 be noted that the upper edges 6 and 7 of the fish-plates are also beveled from end to end

of the rail-joint, as shown in dotted lines in Fig. 1 of the drawings, thereby forming a wedge-shaped clamp that will effectually bind both sections of the rails together. An 55 enlarged portion 9 is formed integral with the fish-plates near the center to give further strength and rigidity to the structure, the recesses 10 being formed in the sides of the rail-joint, which are adapted to receive spikes or 60 other suitable fastening means to fasten the device to the cross-ties.

When it is desired to bind the rails, their ends are inserted into the chair. The inner face of the chair by reason of the central 65 taper, as seen at 7 in Fig. 4, will register throughout with the tapered sides of the web and the upper beveled edge of the chair will enter the beveled portion in the under face of the tread of the rail, as seen in Fig. 3 and 70 shown by dotted line in Fig. 1. Thus the rail will be securely held in position.

It will be noted that various changes may be made in the details of construction without departing from the general spirit of my 75 invention.

Having fully described my invention, what I claim as new, and desire to secure by Letters Patent, is—

1. In a rail-joint, the combination with the 8c rails provided with wedge-shaped portions, fish-plates carrying an integral base, said fish-plates having their inner faces beveled and forming wedge-shaped openings therebetween to engage the web of the rails, substantially 85 as described.

2. In a rail-joint, the combination of the rails having the ends of their web portions wedge-shaped and the under face of their treads adjacent the ends of the rails inclined 90 inwardly, and fish-plates provided with an integral base, said fish-plates having their inner faces and upper edges beveled to engage the web and inclined under face of the rails, substantially as described. 95

In testimony whereof I have hereunto signed my name in the presence of two subscribing witnesses.

ROBERT WEIR, JR.

In presence of—

JOHN GROETZINGER,
C. C. RAYMOND.
